COMPOSITE STENCIL AND FOLDER

Ralph W. Sherman, Montclair, N. J.

Application December 17, 1946, Serial No. 716,699

4 Claims. (Cl. 101—127)

(Granted under the act of March 3, 1883, as amended April 30, 1928; 370 O. G. 757)

1

This application is made under the act of March 3, 1883, as amended by the act of April 30, 1928, and the invention herein described, if patented, may be manufactured and used by or for the Government of the United States of America for governmental purposes without the payment to me of any royalty thereon.

This invention relates to a stencil and associated backing. It particularly relates to a stencil adapted to be passed around the platen roll of a writing machine, and then to be operatively attached to the printing drum of a stencil duplicating machine.

An object of this invention is to provide a stencil that can be cut on an ordinary or narrow-carriage typewriter with the lines of matter running parallel to the longer side of the stencil sheet.

A further object is to provide a stencil composed of two or more stencil pages each of which may be individually stencilled or cut in a narrow-carriage typewriter and thereafter assembled to form a composite long stencil sheet having the lines of printed matter running parallel with the longer side of the sheet.

At present, when it is desired to type on a mimeograph stencil in lines parallel to the longer side of a sheet, which has a length greater than can be accommodated in a typewriter with a 12-inch carriage, it is necessary either to use a wider typewriter or to fold the stencil. Neither recourse is convenient, and the second alternative results in a crease in the stencil that may show in the printed copy. An instance of this is in preparing a two-page leaflet from a single sheet of paper.

To overcome this and to permit use of a narrow-carriage typewriter, my new method and device involves typing two narrow pages separately and then joining the two into a mimeograph stencil of regular size.

Another object is to provide a protective folder for the stencil pages, the folder comprising the backing sheets for the stencil pages and being preferably formed of one sheet, which may have a weakened line of fold.

I attain these objects by the device described in the accompanying drawing, in which:

Figure 1 is a plan view of the folder in open position and looking at the inner faces thereof;

Figure 2 is a side view of Figure 1;

Figure 3 is a view of the composite stencil formed by attaching the two pages to each other, with line c—c superimposed on one of lines d—d;

Figure 4 is a plan view of the folder in folded position with one leaf partly turned back and with parts broken away for clarity.

2

The folder comprises the backing sheets 1 and 2 which are integrally associated or joined along perforated or otherwise weakened fold line 3. Right-hand page 4 of the stencil is glued or cemented to backing sheet 1 of the stencil sheet at edge 5. The left-hand page 6 of the stencil is cemented to backing sheet 2 at edge 7. Backing sheet 2 is provided with keyhole slots 11 for attachment to the studs or pins of a mimeographing drum or other stencil carrier. Sheet 2 is perforated or otherwise weakened along a line 8' immediately below ruled line 8 on left-hand page 6.

Marginal lines 9 on page 6 and 10 on page 4 are provided, within which the typing may be confined. This facilitates use of the invention in preparing a two-page leaflet. Guide lines c—c and d—d are designed to assist in spacing the two pages of printed matter to provide the desired width of margin.

One mode of application of the invention is as follows:

The backing sheet 1 is separated from the backing sheet 2 by tearing along the fold line 3. A sheet of carbon paper is then inserted between each stencil page 4 and 6 and their respective backing sheets, the coated side being next to the stencil paper. Before inserting either stencil page, and its backing sheet, into a typewriter, a strip of creased paper may be placed over the edge marked "top" to prevent the tearing or wrinkling of the stencil. Both the left- and right-hand pages may then be typed along lines parallel to the top edge.

When both pages of stencil have been typed or cut, the right-hand page of the stencil is detached along the perforated line c—c and then attached to the right edge of the left-hand page. Line c—c is superimposed on either one of the lines d—d ruled on page 6. By providing a number of lines d—d at pre-chosen distances from the ruled margin 9 on the left-hand page the two pages may be conveniently and accurately spaced to obtain the desired width of margin. For example, when line c—c is spaced $\frac{1}{8}$ inch from the left margin on the right-hand page and lines d—d are respectively $\frac{1}{8}$ inch and $\frac{3}{8}$ inch from the right margin of the left-hand page, a $\frac{5}{8}$ inch or a $\frac{3}{4}$ inch space between the two pages is obtained by placing line c—c over a line d—d.

Any conventional type of gum or cement may be used. It is preferred to employ self-adhering gummed portions, or cemented strips, or strips of pressure adhesive, which require only the pressing together of the two parts to be joined. I prefer to employ a strip of pressure adhesive at '12 on outer face of stencil page 6 and at '13 on the under face of stencil page 4.

Backing sheet 1 need not be attached to backing sheet 2 at the edge 3. Any one of the four edges of sheet 1 may be attached to or integral with any one of the four edges of sheet 2.

Having thus described my invention, I claim:

1. A stencil comprising an elongated backing sheet, said sheet having a weakened transverse line dividing it into a first section and a second section, the first section having a row of slots adjacent an edge thereof for engagement with operative elements associated with a duplicating machine, a stencil sheet on each of said sections, each of said stencil sheets being separate and independent of the other and secured along a transverse edge thereof to its corresponding backing sheet section, the stencil sheet of the second section having a transverse weakened line adjacent the edge thereof which is secured to its backing sheet section, the stencil sheet of the first section having a transverse gummed edge opposite the edge thereof that is secured to its backing sheet section, a marginal reference mark carried by the stencil sheet of the first section adjacent the gummed edge and another marginal reference mark carried by the stencil sheet of the second section adjacent the edge thereof that is secured to its backing sheet section, said marginal reference marks being adapted to be placed in registry with each other, whereby said sections with their corresponding stencil sheets may be separated from each other along said first mentioned weakened line, and the stencil sheet of the second section separated from said second section and secured to the stencil sheet of the first section by means of said gummed edge with the marginal reference marks in mutual registry.

2. A composite stencil and folder comprising an elongated backing sheet having a transverse line of fold intermediate its ends and a transverse row of apertures for engagement with operative elements associated with a duplicating machine, the apertures being to the right of the line of fold when the backing sheet is unfolded, a left hand page stencil sheet permanently attached to the backing sheet along a transverse edge of said stencil sheet to the right of the row of apertures, a separate and independent right hand page stencil sheet temporarily attached to that part of the backing sheet which is left of the line of fold, a marginal reference mark carried by the right hand page stencil sheet along its left transverse edge, another marginal reference mark carried by the left hand page stencil sheet along its right transverse edge, one of said two transverse edges being gummed, said marginal reference marks being adapted to be superposed in registry with each other, whereby the two stencil pages are protected within the folded backing sheet and upon tearing along the line of fold each stencil page remains attached to its section of the backing sheet and may be individually stencilled in a narrow-carriage typewriter and thereafter the stencil pages assembled by superposing the marginal reference marks to form a composite long stencil sheet having the lines of two pages of printed matter running parallel with the longer side of the sheet.

3. A composite stencil and folder comprising an elongated backing sheet having a transverse line of fold intermediate its ends and a transverse row of apertures for engagement with operative elements associated with a duplicating

machine, a left hand page stencil sheet permanently attached to the backing sheet along a transverse edge of said stencil sheet, said left hand page being on one side of the line of fold, a separate and independent right hand page stencil sheet temporarily attached to that part of the backing sheet which is on the other side of the line of fold, a marginal reference mark carried by the right hand page stencil sheet along its left transverse edge, another marginal reference mark carried by the left hand page stencil sheet along its right transverse edge, one of said two transverse edges being gummed, said marginal reference marks being adapted to be superposed in registry with each other, whereby the two stencil pages are protected within the folded backing sheet and upon tearing along the line of fold each stencil page remains attached to its section of the backing sheet and may be individually stencilled in a narrow-carriage typewriter and thereafter the stencil pages assembled by superposing the marginal reference marks to form a composite long stencil sheet having the lines of two pages of printed matter running parallel with the longer side of the sheet.

4. A composite stencil and folder comprising an elongated backing sheet having a transverse line of fold intermediate its ends and a transverse row of apertures, for engagement with operative elements associated with a duplicating machine, the apertures being adjacent and to the right of the line of fold when the backing sheet is unfolded, a left hand page stencil sheet permanently attached along its left transverse edge to the backing sheet adjacent and to the right of said apertures, a separate and independent right hand page stencil sheet temporarily attached at its left transverse edge to that part of the backing sheet which is to the left of the line of fold, a marginal reference mark carried by the right hand page stencil sheet along its left transverse edge, another marginal reference mark carried by the left hand page stencil sheet along its right transverse edge, one of said two transverse edges being gummed, said marginal reference marks being adapted to be superposed in registry with each other, whereby the two stencil pages are protected within the folded backing sheet and upon tearing along the line of fold each stencil page remains attached to its section of the backing sheet and may be individually stencilled in a narrow-carriage typewriter and thereafter the stencil pages assembled by superposing the marginal reference marks to form a composite long stencil sheet having the lines of two pages of printed matter running parallel with the longer side of the sheet.
